INSTRUMENT FOR ENCIPHERING AND
DECIPHERING

Norman Alexander Smith, Adelaide, Australia

Application January 5, 1934, Serial No. 705,374
In Australia January 28, 1933

6 Claims. (Cl. 35—3)

This invention relates to an instrument for enciphering and deciphering.

Its object is to enable a message or communication to be changed into a secret cypher after such message has been associated with a code sentence or arrangement of letters known to the recipient, the message being deciphered by the use of a similar instrument.

The instrument comprises a base member, a slide member slidable thereon, and a rotatable member rotatable about a pin in the base member and geared to the slide member, the base member and the slide member each bearing the letters of the alphabet so positioned that by moving the slide member any letter upon it can be brought adjacent any letter upon the base member, the rotatable member also bearing the letters of the alphabet so positioned that when any letter upon the slide member is brought adjacent any letter upon the base member a letter is indicated upon the rotatable member.

I prefer to use such gearing between the slide member and the rotatable member that the rotatable member can be set in different relationship to the slide member.

It will be obvious that the letters of the alphabet can be replaced by other suitable symbols provided the sender and the recipient know which letters, or perhaps numbers, the symbols represent.

In order that the invention may be the more clearly understood I will now describe it with reference to the accompanying drawing in which is shown the construction of the device and the arrangement of letters which I prefer.

Fig. 1 is a perspective view of my device showing the slide member positioned to one side.

Fig. 2 is a central longitudinal section through the base member showing particularly the rotatable member and some of the parts associated therewith.

Fig. 3 is a plan of the instrument with the base in section and showing the slide member positioned centrally, or in what I term the zero position. The letters are shown on the rotatable member only.

Fig. 4 is a cross section of the instrument as on line 4—4 of Fig. 3.

Fig. 5 is a sectional perspective view of the rotatable member.

The base member 1 is formed with a guideway 2 extending from end to end, and in this guideway the slide member 3 is supported.

The slide member 3 fits neatly into the said

guideway and has a small finger-piece 4 by means of which it is moved to right or left as required.

The rotatable member 5 comprises a disc 6 and a pinion 7, the disc and pinion being supported upon a pivot pin 8 in the base member 1. The disc 6 and pinion 7 are connected together by a ratchet wheel 9 and a spring-loaded pawl 10, the wheel 9 being integral with the pinion 7 and the pawl 10 being pivoted to the disc 6. The pressure of the pawl 10 upon the ratchet wheel 9 causes all the parts of the member 5 to rotate in unison, but when the disc 6 is held the pinion 7 may be turned in clockwise direction. Portion of the disc 6 of the rotatable member 5 is visible through a window 11 in the top of the base member 1.

On the underside of the slide member 3 is a rack 12 which engages the pinion 7 of the rotatable member 5.

The slide member 3 has a pin 14 which projects into a slot 15 formed in the base member 1, the purpose of which is to limit the movement of the slide member 3.

The holding of the rotatable member 5 when required is effected by pressing a stop button 16 on the base member 1, and this button, through a bell crank 17, operates a stop bolt 18 which engages one of a series of notches 20 in the edge of the disc 6. Simultaneously the button 16 operates a bell crank 21 which projects a stop 22 for engagement by a pin 23 upon the slide member 3 and so limits the return of the member 3 to its central position. The stop button 16 and its associated parts are returned by a spring 24.

Along the face of the base member 1, adjacent the slide member 3, is displayed a row 25 of letters arranged in alphabetical order. Along the face of the slide member 3, adjacent the row of letters on the base member 1, is displayed a second row 26 of letters arranged and spaced similarly to the row 25 of letters. Set around the edge of the disc 6 of the rotatable member 5 is a third row 27 of letters also corresponding to the first row 25 of letters. The row 27 of letters is hereinafter spoken of as key letters.

The rotatable member is set so that any desired key letter will appear in the window 11 when the instrument is set at zero position, that is with the slide member 3 in central position in the base member 1.

This setting is accomplished by turning the rotatable member by moving the slide member 3 to the right until the desired key letter appears in the window, then depressing the stop button 16 to prevent rotation of the disc of the rotatable member 5, and then moving the slide

member 3 to the left to zero position, movement past such position being prevented by the stop 22 and pin 23. This movement gives approximately a half revolution of the rotatable member 3, and for greater movement the action is repeated.

Instead of using the ratchet wheel 9 and the pawl 10 to effect setting of the rotatable member 5 relative to the slide member 3 the slide member may be lifted to disengage the rack 12 from the pinion 7 and the rotatable member set to the desired key letter, the slide member then being repositioned.

In enciphering a message the instrument is used in the following manner. The device is first adjusted so that for a zero setting of the slide member 3 the rotatable member 5 is positioned to show the key letter through the window 11, such key letter being known to the recipient. Assume the key letter to be "S" which corresponds to the setting shown in the drawings.

An arrangement of letters or words comprising the code sentence, which is also known to the recipient, is written upon a pad or elsewhere and the message is written letter for letter beneath the code sentence. Suppose the start of the code sentence to be "Adelaide" . . . and the start of the message to be "New" . . . This is written upon the pad thus

35 The slide member 3 is now moved until the "N" upon it comes adjacent the "A" on the base member 1. The movement of the slide member rotates the rotatable member 5 to show "F" through the window 11. This is the first letter of the cipher.

40 The slide member 3 is next moved until the "E" upon it comes adjacent the "D" on the base member 1. This will be found to give the letter "R" as the second letter of the cypher.

45 The slide member 3 is then moved to bring the "W" upon it adjacent the "E" on the base member, whereupon the "A" will appear in the window 11 as the third letter of the cypher.

The start of the cypher which is transmitted to the recipient is thus "FRA".

50 Deciphering is effected in the following manner.
The instrument is adjusted by the recipient so that for the zero setting of the slide member 3 the key letter "S" (which is known to him) appears in the window 11.

55 The code sentence (which is also known to the recipient) is next written by him upon a pad or elsewhere with the cypher beneath it thus

The slide member 3 is then moved to bring the "F" upon it adjacent the "A" on the base member 1. The letter "N" will now appear in the window 11 and forms the first letter of the message.

The slide member 3 is next moved to bring the "R" upon it adjacent the "D" on the slide member. This brings the letter "E" into the window forming the second letter of the message.

Similarly when the "A" of the slide member 3 is brought adjacent the "E" on the base member 1 the letter "W" will appear in the window forming the third letter of the message.

We thus have the beginning of the message
"New" . . .

In the above described instrument I have shown the letters upon the members in correct alphabetical order, which sequence is preferable but which is not indispensable. The order of the letters must however, for the above described manner of using the instrument, be the same on each of the members.

I have shown the alphabet duplicated upon the base member 1 but this is only for convenience of operation and in many cases reduces the extent of movement of the slide member 3, for example to move the slider so that the "N" comes adjacent the "Z" instead of adjacent the "A" as shown in Fig. 1 it is only necessary to move through one space. As the letters are continuous around the rotatable member any particular letter on the slide member 3 may be associated with any particular letter on the base member 1 irrespective of which alphabet the letter is in, for example referring to Fig. 1 the "N" on the slide member may be positioned adjacent either of the "A's" on the base member, both positions bring the "F" into the window 11. 10 15 20 25

It is obvious that different systems of working the instrument can be formulated but I prefer the system set forth as by its use the enciphering and deciphering is carried out in the same manner in each case, the code sentence being associated with the letters upon the base member 1, the message to be sent or the message (in cypher) received being associated with the slide member 3, and the result (the cypher or the enciphered message) being read off from the rotatable member 5 through the window 11 in the base member 1.

What I claim is:

What I claim is:

1. An instrument for enciphering and deciphering comprising, a base member having the letters of the alphabet displayed along its face, a slide member slidably supported in the base member and having the letters of the alphabet displayed along its face adjacent the letters upon the base member, a rotatable member carried upon a pin on the base member, and having the letters of the alphabet upon it, and gearing connecting the rotatable member to the slide member.

2. An instrument according to claim 1 characterized in that the gearing comprises, a rack upon the slide member, a pinion forming part of the rotatable member, and a ratchet and pawl connecting the pinion to the remainder of the rotatable member, the pinion being in engagement with the rack. 55

3. An instrument according to claim 1 characterized in that the rotatable member is positioned within the base member, and by a window in the base member through which only one letter of the rotatable member is visible at one time.

4. An instrument for enciphering and deciphering comprising, a base member having the letters of the alphabet displayed along its face, a slide member slidably supported on the base member and having the letters of the alphabet displayed along its face adjacent the letters upon the base member, a toothed rack secured to the slide member, a disc forming part of a rotatable member carried upon a pin in the base member and having the letters of the alphabet displayed along its face, a pinion forming the other part of the rotatable member supported coaxially with the disc and being in engagement with the rack, a ratchet upon the one part of the rotatable mem- 70 75

ber and a pawl upon the other part of the rotatable member to connect the pinion to the disc.

5. An instrument according to claim 4 characterized by, a stop button upon the base member, 5 a stop bolt connected therewith, and notches in the disc one adjacent each letter thereon, the stop bolt adapted when the stop button is depressed to engage a notch in the disc and hold the disc.

10 6. An instrument according to claim 4 charac-

terized by a stop button upon the base member, a stop bolt connected therewith adapted when the button is depressed to engage notches in the disc of the rotatable member and hold such disc, a further stop connected to the stop button, a pin upon the slide member, the stop adapted when the stop button is depressed to project into the path of the pin to prevent return of the slide member past the zero position.

NORMAN ALEXANDER SMITH. 10
